serves to close the fuel line should a back pressure occur in the line between the valve and burner.

It is to be understood that the form of our invention herein shown and described is to be taken as a preferred example of the same and that changes in the shape, size and arrangement of the parts may be made without departing from the spirit of the invention or the scope of the subjoined claims.

Having thus described our invention, we claim:

1. A fuel oil and air mixing device comprising a chamber adapted to contain a supply of fuel oil, a mixing tube disposed centrally of said chamber having its upper end opening into the chamber above the level of the oil, said tube having a valve seat in its upper end and diametrically opposed orifices with valve seats adjacent its lower end, a fuel line leading from the lower end of said mixing tube, an air supply conduit connected to the upper end of said chamber for supplying a continuous stream of air under pressure to the chamber above the level of the fuel oil, a valve member co-acting with the valve seat in the upper end of said mixing tube for regulating the flow of air through said tube, and valve members co-acting with the valve seats of the orifices in the lower end of said tube for

regulating the opposed streams of oil forcibly ejected from the orifices across said tube through the stream of air passing therethrough whereby the oil is broken into fine particles for thorough mixing with the stream of air.

5 2. A device as described in claim 1 including a fuel atomizer connected to said fuel line consisting of a solid body having a series of parallel longitudinal passages therethrough.

10 3. A device as described in claim 1 including a fuel atomizer connected to said fuel line and a ball valve interposed in the fuel line actuated by the back pressure to close said fuel line.

FRED BROUSSEAU.
PHILIP J. BROUSSEAU.
